HENRY G. WERNIMONT, OF WASHINGTON, DISTRICT OF COLUMBIA.

CLOTHESLINE.

1,333,520.

Specification of Letters Patent.

Patented Mar. 9, 1920.

Application filed January 16, 1919. Serial No. 271,388.

To all whom it may concern:

Be it known that I, HENRY G. WERNIMONT, a citizen of the United States, residing at Washington, District of Columbia, have invented certain new and useful Improvements in Clotheslines; and I do hereby declare the following to be a full, clear, and exact description of the invention, such as will enable others skilled in the art to which it appertains to make and use the same.

The present invention relates to clothes lines, and more especially to those composed of wire links, it being the object of the invention to provide a clothes line of that character, the links of which are bent from wire in a novel and improved manner, in order to enhance the utility and efficiency of the clothes line.

One of the specific objects of the invention is the provision of such a clothes line wherein the links can be readily assembled and taken apart, for lengthening or shortening the line, and for making repairs, and the like, the links being of novel formation in order that they can be readily taken apart and coupled together.

A further object is the provision of a clothes line link comprising a clamping or gripping strand twisted or wound helically around a draft strand to receive and clamp or pinch the clothes, and means whereby the clothes can be readily introduced, and whereby the gripping strand can be wound up tighter from time to time, in order that the tension of the gripping or clamping portions of the link can be adjusted at will in an easy and convenient manner.

It is also the object of the invention to provide a link having the characteristics above noted and which can be readily bent from a length of wire, so as to be capable of cheap and simple manufacture, each link being readily made complete by itself, and the links assembled by the user or salesmen.

With the foregoing and other objects in view which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing wherein:—

Figure 1 is a side elevation showing one complete link coupled to adjoining compan-

ion links, and showing in dotted lines the position of the gripping strand for inserting the clothes.

Fig. 2 is a similar view showing the gripping strand unwound and in its natural position, to illustrate how the link can be manipulated for detaching it from and attaching it to the companion link, and to also illustrate how the gripping strand can be wound upon and unwound from the draft strand.

Fig. 3 is a cross section taken on the line 3—3 of Fig. 1.

Each link of the clothes line is bent from a suitable length of resilient wire of suitable quality, and comprises a draft strand 1 provided at one end with an eye or loop 2, formed by bending back the respective terminal of the wire, which is also preferably looped around the strand 1 as at 3, and then extended through the eye or loop 2 as at 4, to lock the terminal in place, and also prevent the loop 2 from opening under the strains. This loop 2 constitutes means for attaching the respective end of the strand 1 to the next link.

The strand 1 is provided at its other end with a loop or bend 5, formed by doubling the wire, and from the loop 5 extends a gripping strand 6 that is slightly shorter than the draft strand 1. In the natural position of the strands 1 and 6, when they are unwound, they cross one another adjacent to the loop 5 as seen in Fig. 2, and are arranged at an acute angle. In this position of the strands, it is readily apparent that the gripping strand 6 can be inserted through the loop 2 of the adjacent link, to couple the links together, or the strand 6 can be drawn through said loop for detaching the links. This permits the links to be readily coupled and uncoupled when the gripping strands 6 of the links are unwound from the strands 1. Consequently, the line can be readily lengthened and shortened by adding or removing links, and, furthermore, the links need not be assembled at the factory but can be sold individually in any desired quantity, the salesmen or purchaser assembling the desired number of links.

The gripping strand 6 is adapted to be twisted around or wound helically upon the strand 1, as seen in Fig. 1, so that the clothes or other articles to be suspended, will be clamped or gripped between the two strands. In this connection, the free end of

the strand 6 has a portion 7 extending at an angle therefrom and bent back to provide an opposite parallel portion 8 constituting with the portion 7 an operating loop 9 that 5 is movable transversely over and around the strand 1. The portion 8 is provided with a finger 10 bent back therefrom toward the loop 9 and forming a U-shaped seat 11 within the throat of the loop for the strand 1, 10 said finger 10 constituting the other terminal of the wire which, owing to the doubling of the wire between its ends, brings the two terminals close together, one being used for connection with the adjacent link, and the 15 other terminal being free and employed to retain the gripping strand 6 in place upon the draft strand 1.

In winding the strand 6 around the strand 1, the free terminal of the strand 6 is moved 20 back and forth across the opposite sides of the strand 1. Thus, taking the parts as seen in Fig. 2, the free terminal of the strand 6 is moved toward the observer and then moved downwardly across the near side of the 25 strand 1. The free terminal of the strand 6 is then moved away from the observer and upwardly across the opposite side of the strand 1, the loop 9 remaining in its upwardly projecting position. This is repeated 30 until the number of twists have been made with the portion 7 extending upwardly at one side of the strand 1. The loop 9 is then pushed downwardly so that the strand 1 passes between the portion 7 and 35 the finger 10 which are spaced apart, said finger 10 being located between the portions 7 and 8. Then, when the loop 9 is released, the strand 6 will move against the strand 1, bringing the strand 1 within the seat 11. 40 The tendency for the strand 6 to assume its normal straight position serves to swing the terminal of the strand 6 against and past the strand 1, so if it were not for the seat 11, the strand 6 would loosen itself and unwind, 45 it being kept in mind that the strand 1 is not turned about its axis in winding it around the strand 1 so that there is no tendency to rotate around the strand 1. If it is desired to twist the strand 6 another time 50 around the strand 1, should the parts loosen due to continued use, or should it be desired to disconnect the links, the loop 9 is pushed toward the strand 1, thereby removing the strand 1 from the seat 11 and the loop 9 is 55 then shifted laterally so that the strand 1 can move between the portion 7 and finger 10. This frees the terminal of the strand 6 so that it can be either unwound or wound another turn or two.

60 In using the clothes line, the loop or member 9 is pressed by the finger and thumb toward the strand 1, thus forcing the end of the strand 6 away from the strand 1, and forming a loop or entrance as seen in dotted line in Fig. 1, in order that the article can

be readily inserted through the loop or opening provided and then moved longitudinally toward the opposite end of the link between the strands 1 and 6. This not only causes said strands to grip the article, but the article in being moved lengthwise, will be twisted or turned around the strands 1 and 6, due to the twisted position thereof, so that the article will be firmly held against accidental detachment. The loop 9 is released when the article is inserted, and more than one article can be gripped by each link if desired, they being moved between the strands one at a time, and each will be firmly held.

To release the strand 6, for the purpose of detaching the links, or to regulate the tension, the loop 9 is pressed toward the strand 1, and said strand then brought or worked between the portion 7 and finger 10 to move the strand 1 out of the loop 9 at one side of the seat 11. This disengages the respective terminal of the wire or strand 6 from the strand 1, and permits the strand 6 to unwind to the position shown in Fig. 2. 90 The links can then be easily separated, the strand 6 and its terminal loop 9 being readily withdrawn from the respective loop 2 of the adjacent link. The releasing of the strand 6 also enables it to be wound tighter 95 on the strand 1, or to be loosened. Thus, when the strand 6 is unwound, it can be re-wound the desired number of turns, either less or more than before, according to the tension desired. It being noted that the 100 more times the strand 6 is wound around the strand 1, the greater will be the tension. This also permits the tension to be increased from time to time, so that if the tension relaxes due to the continued use of the line, 105 the strand 6 can be readily released from the strand 1 and wound up tighter, providing a simple and effective way for adjusting the tension. The natural position of the strands 1 and 6 as shown in Fig. 2, enables the twisting to be started easily, and furthermore, the loop 5 will be closed so as not to permit the links to become detached accidentally, although the strands 1 and 6 can be sprung apart when the loop 2 passes the point of 110 crossing of said strands 5.

Having thus described the invention, what is claimed as new is:—

A clothes line link comprising a straight draft strand having a loop at each end, a 120 normally straight gripping strand extending from one loop and adapted to be wound a number of times around the draft strand by passing the free terminal of the gripping strand back and forth at opposite sides of the draft strand, and having a tendency to straighten out and unwind, said free terminal being provided with a portion extending at an angle therefrom and having a portion bent back forming a loop to surround 125

and extend at an angle from the draft strand when the gripping strand is wound thereon, said loop affording means for pushing the free terminal of the gripping strand away from the draft strand, and the last named portion having a finger bent back between said portions to form a seat to receive and move into engagement with the

draft strand when the loop moves away from the draft strand, and to permit the draft strand to move between said finger and first named portion out of the loop.

In testimony whereof I have signed my name to this specification.

HENRY G. WERNIMONT.
